UNITED STATES PATENT OFFICE.

CARL BJORK, OF WILMINGTON, CALIFORNIA.

ROWLOCK.

Application filed September 10, 1925. Serial No. 55,498.

An object of this invention is to provide a rowlock that will give greater freedom of movement of the oar and increase the ease and convenience in rowing and to make provision whereby the oarsman can row standing or sitting.

An object is to provide a superior rowlock which can be used in sculling.

Another object is to make convenient provision for allowing oars and oar-locks to be locked to the boat by a single fastening.

Heretofore fishermen and other boatmen likely to ride rough seas or to land or go out through heavy surf hesitate to use any rowlock, except the thole pin rowlock, as it requires great freedom of oars to avoid swamping the boat in such seas or surf.

An object of this invention is to provide a simple construction and arrangement whereby an oarsman can handle his oar with greater freedom than heretofore and without any danger of unshipping his oar and also with minimum lost motion and with freedom to adjust the oars toward and from the center of the boat to accommodate different modes of rowing; to feather the oar when rowing, and also to insert the oar deep into the water when standing up and sculling or rowing.

Another object is to minimize the danger of exerting a leverage tending to break the rowlock or the socket in the boat gunnel.

The invention includes the simple construction of the rowlock proper and also the arrangement and combination of the rowlock and oar.

Another object of the invention is to minimize wear and tear on the oar, and on the muffle sleeve.

This invention relates to the construction of one-piece rowlocks.

I accomplish the objects of this invention by constructing a one-piece rowlock comprising a shouldered shank or swivel pin adapted to rest on and revolve in the gunnel of the boat; and an eye coaxial with such pin having an elongated orifice formed by a semi-circular base, and a semi-circular arch or top guard of the same radius, and vertical thole pins forming a guide or slideway for the oar, the space between such thole pins being equal to the diameter of the semi-circle of the base and arch and slightly greater than the diameter of the cylindrical portion or muffled shank of the oar which is to work in the rowlock.

By this construction and arrangement an oar in place in the rowlock, mounted on the gunnel of the boat, can be slid endwise through the rowlock with as great freedom as through the space between ordinary thole pins and this is true at any angle at which the oarsman may hold the oar, either sitting or standing; and the rowlock is practically as simple and easy to construct as a rowlock having a circular eye and is free from the restrictions of movement and the jamming and crushing the oar is liable to in use with a circular eye.

Other objects, advantages and features of the invention may appear from the accompanying drawing, the subjoined detailed description and the appended claims.

The accompanying drawing illustrates the invention.

Figure 1 is a perspective view of a rowlock constructed in accordance with this invention, and an oar in place with a muffle sleeve and collar thereon; the oar being broken to contract the view.

Fig. 2 is an enlarged elevation of the rowlock with a fragment of the oar in position for sculling; and a fragment of the stern of the boat; dotted lines indicate a horizontal position of the oar.

Fig. 3 is an elevation on line x^3 , Fig. 2, looking in the direction of the arrow with the oar in the position shown in dotted lines in Fig. 2. Broken lines indicate that a chain may be inserted through the eye to secure the rowlock with its oar when the same are left without an attendant.

Fig. 4 is a vertical section of the rowlock on line x^4 , Fig. 3.

Fig. 5 is a horizontal cross-section on line x^5 , Fig. 3.

1 is the usual swivel pin constructed in a manner common to some other rowlocks, and with a collar 2, which rests on the gunnel 3. Above the collar this rowlock is constructed with a novel vertically elongate oar holding eye or ring comprising an oar rest 4, two parallel upright oar guiding sides 5 resembling thole pins, and above the thole pins, a top guard 6, said rest, thole pin and top guard being of one piece with the swivel pin.

The oar bearing surfaces of the rest, the edges of the base the top guard and the thole pins, are rounded as indicated, in Figs. 4 and 5 to facilitate the movement of the oar and to avoid any likelihood of crushing,

jamming or wearing the oar or the muffle sleeve and collar thereon.

The length of the opening 7 in the ring from the rest 4 to the arched guard 6 is three times the radius of the oar. That is to say, the length of the opening of the ring from the center bottom point 8 to the center top point 9 is one and one-half times the width across the opening from thole pin to thole pin; so that the oar 10 is given full lateral support throughout the entire possible bodily movement of the oar from bottom to top of the ring.

The parallel intermediate upright sides 15 are spaced apart the distance required to freely accommodate the oar without lost motion.

The oar which is adapted to be locked by this novel rowlock is provided with a leather sleeve 11 and the stop collar 12. The stop collar 12 is of such diameter that the oar cannot be withdrawn away from the blade end 13 and the blade of the oar prevents the oar from being withdrawn toward the handle end 14 and the open space between the oar 10 and the arch 6 is sufficient to allow a chain or other fastening device, not shown, to be inserted through the eye of the rowlock as indicated at 15 in Fig. 3, or 30 through the eyes of more than one rowlock, and such chain may be fixed to any suitable part of the boat so that when the boatman wishes to leave the boat unattended he will simply withdraw the rowlock and 35 oars, lay the oars in the bottom of the boat and pass the fastening device as the chain or hasp, not shown, above the oar and will then lock such chain, thus securing all of the oars through the rowlock eyes of which 40 the fastening device has been passed.

The vertical elongate character of the eye allows all of the necessary movement to enable the oarsman to row in sitting or standing position or to scull the boat with perfect 45 freedom, and this is effected without any lost motion of the oar, and without danger of breaking the eye, by reason of the oar binding against the top and base of said eye.

I claim:

50 1. A rowlock having an elongated oar holding eye provided with a rounded oar supporting base, a rounded oar holding top guard arch and parallel sides forming vertical oar guiding slides.

55 2. A rowlock having a vertically elongated eye provided with upright parallel thole pins and a top guard.

3. A one-piece rowlock having an elongated eye with thole pin parallel sides; and 60 an arched guard at the top.

4. A rowlock having thole pins forming the sides of an elongated eye and provided with a semi-circular base and top, and having a length from center bottom to center 65 top of the eye, practically equal to one and

one-half the width between the parallel sides of the eye.

5. The combination with an oar having a collar between its handle and blade, of a rowlock having an elongated eye, the sides 70 of which are parallel, and spaced apart practically the diameter of the oar, and being in length practically one and one-half times the radius of the oar; said collar being of greater diameter than the oar so that it 75 will not pass through the eye, whereby both rowlock and oar may be fastened when not in use, by a fastening extending through the space between the oar and the top of the eye.

6. A rowlock having an eye comprising a curved base, two thole pins and a top arch; the inner faces of the thole pins being tangent to the inner faces of the base and arch.

7. A rowlock of the swivel pin type having an eye centrally located on the pin and provided with two thole pins connected together at bottom and top by semi-circular base and semi-circular arch, the space between the thole pins being slightly greater 80 than the diameter of the muffled shank of the oar to be used therein and the arches being tangent to the adjacent sides of the thole pins and spaced apart practically three times the radius of the semi-circles 85 of said base and arch.

8. A rowlock of the swivel pin type having an eye centrally located on the pin and provided with two thole pins connected together at bottom and top by semi-circular 90 base and semi-circular arch, the space between the thole pins being slightly greater than the diameter of the muffled shank of the oar to be used therein and the arches being tangent to the adjacent sides of the 95 thole pins and spaced apart practically three times the radius of the semi-circles of said base and arch, the edges of the base, the top guard and the thole pins being rounded to facilitate the movement of the oar and to 100 avoid likelihood of crushing, jamming or 105 wearing the oar or the muffled sleeve and collar thereon.

9. The combination with an oar having a collar between its end and blade; of a rowlock having a vertically elongated eye provided with parallel thole portions, spaced apart a distance slightly greater than the diameter of the oar and a distance less than the diameter of the collar, and being in length, practically one and one-half times the radius of the oar, whereby both row-lock 110 and oar may be fastened by a fastening extending through the space between the oar and the top of said eye.

10. In combination with an oar having a blade and a muffled shank provided with a collar, of an oar-lock of the swivel pin type having a ring integrally formed and centrally located with respect to the pin, said ring 115

being provided with two vertically extending thole pins connected together at bottom and top by a semi-circular base and a semi-circular arch, the space between the thole pins being slightly greater than the diameter of the muffled shank of the oar to be used therein and the arches being tangent to the adjacent sides of the thole pins and spaced apart practically three times the radius of the semi-circles of said base and arch, so that the oar may be given full lateral support throughout its entire possible bodily movement from the bottom to the top of the ring.

11. An oar-lock of the swivel pin type having a ring centrally located on the pin and provided with parallel intermediate upright thole portions connected together at

bottom and top by a semi-circular base and a semi-circular arch, the space between the thole portions being slightly greater than the shank of the oar to be used therein and the arches being tangent to the confronting sides of the thole portions and spaced apart practically three times the radius of the semi-circles of said base and arch, the edges of the base, arch and thole portions being rounded to facilitate the movement of the oar and to permit full lateral support throughout the entire possible bodily movement of the oar from bottom to top of the ring.

In testimony whereof, I have hereunto set my hand at Los Angeles, California, this 31st day of August, 1925.

CARL BJORK.
